AUTOMATIC INFEEF MECHANISM FOR
GRINDING MACHINES

Jacob Decker, Cincinnati, Ohio, assignor to Cincinnati Grinders Incorporated, Cincinnati, Ohio, a corporation of Ohio

Application April 12, 1940, Serial No. 329,333

12 Claims. (Cl. 51—95)

This invention relates to grinding machines and more particularly to automatic cycle control mechanism therefor.

One of the objects of this invention is to provide a novel and improved infeed cycle control mechanism for a grinding machine.

Another object of this invention is to provide an improved hydro-mechanical infeed mechanism which is simple and rugged in construction and positive in operation.

A further object of this invention is to provide an improved mechanical mechanism for infeeding a grinding wheel support which is powered hydraulically whereby the positive features of mechanical operation and the advantages of hydraulic control may be obtained in a single structure.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is an elevational view partly in section of a machine embodying the principles of this invention.

Figure 2 is an enlarged detail section on the line 2—2 of Figure 1.

Figure 3 is a section on the line 3—3 of Figure 2.

Figure 4 is a section on the line 4—4 of Figure 3.

Figure 5 is a diagrammatic view of the hydraulic control circuit.

Referring to Figure 1 of the drawings the reference numeral 10 indicates in general the bed of the machine, and the reference numeral 11 indicates the work support which is slidably supported by the flat and V guides 12 and 13 respectively formed on the bed. A grinding wheel 14 is rotatably mounted on a grinding wheel support or slide 15 which is relatively movable with respect to a sub-support 16 toward and from the work support 11. The grinding wheel 14 may be powered in a conventional manner by an electric motor 17 carried by the support 15.

This invention deals with an improved automatic infeed cycle control mechanism for effecting plunge cut grinding operations on surfaces whose axial length is less than the width of the

grinding wheel face. In view of this, no mechanism has been shown for traversing the table since such mechanism forms no part of the present invention but it will be understood that any suitable traversing mechanism may be employed for that purpose.

The final driving elements of the infeeding mechanism of this invention consist of a rack 18 which, as shown in Figure 1 is integral with the slide 15, and a pinion 19 supported in engagement with the rack by a shaft 20, the shaft passing centrally through the support 16 whereby the subsupport 16 may be rotatably adjusted about the axis of the shaft 20 to vary the plane of rotation of the grinding wheel.

Referring to Figure 2, the shaft 20 has a gear 21 keyed thereto in a position to intermesh with rack teeth 22 formed on the side of an elongated piston 23 slidably mounted in a cylinder 24. A set screw 25 engages a longitudinally extending groove 26 formed in the piston for preventing rotation thereof and maintaining the rack teeth in proper mesh with the gear 21. The piston 23 constitutes a fluid operable member for shifting the grinding wheel support at a rapid traverse rate as well as at a feed rate, there being additional mechanism provided for controlling the rate of feed as will be described hereafter.

This additional mechanism includes a worm wheel 27 and an intermeshing worm 28, the worm being mounted in a housing 29. The worm 28 has integral reduced bearing portions 30 and 31 projecting axially from opposite ends thereof, which are supported by anti-friction needle bearings 32 in sleeves 33 and 34. The sleeves are held against rotation by set screws 35 which engage longitudinally extending slots 36 cut in the periphery of the sleeves. Although the bearing portions rotate relative to the sleeves, washers 37 are provided on the bearing portions so that the worm and sleeves move as a unit in the bore 38 of the housing. This bore is provided with end stops 39 and 40 which engage the ends of the sleeves to define the amount of axial movement of the worm.

Since the worm wheel 27 is keyed to the shaft 20 for movement thereby it will be apparent that these end stops define the amount of movement that can be imparted to the wheel slide by the piston 23.

The end stop 39 determines the return position of the wheel slide which is also the starting position for an automatic infeed cycle. This position may be varied, however, relative to the worm by rotating the worm through the shaft 41 which

has a telescoping spline connection with the shaft 41 which, as shown in Figure 1, is provided with a gear 42 which intermeshes with a pinion 43 mounted on the end of a manually rotatable shaft 44. This shaft extends to the front of the machine and is provided with a hand wheel 45 as well as a pick feed wheel 46. By rotating the hand wheel 45, the worm wheel 27 may be rotated without changing the axial position of the worm whereby the grinding wheel slide and the piston 23 are caused to take up a new return position. Therefore, the cylinder 24 is made sufficiently long to accommodate all the positions which the grinding wheel slide might have. When the wheel slide is in a return position hydraulic pressure is always connected to the left end of cylinder 24 whereby the worm wheel 28 is held against positive stop 39, thereby preventing axial movement of the worm during rotation thereof to effect movement of the wheel slide. It will thus be apparent that the hand wheel 45 changes the zone of movement of the piston 23.

An automatic cycle is initiated by moving the valve plunger 47 of the cycle control valve 48 to the left as viewed in Figure 5. This valve has two pressure ports 49 and 50 which are connected by a common channel 51 to a pump 52 which has an intake 53 through which fluid is drawn from a reservoir 54. The channel 51 has a branch 55 leading to pressure port 56 of the feed control valve 57.

In the stop position the valve plunger 58 is to the right whereby the annular groove 59 interconnects port 56 to port 59' and thereby to channel 60 which leads to port 61 located in the left hand end of the cycle control valve 48. It will thus be apparent that fluid pressure entering opposite ends of the valve casing 48 through ports 50 and 61 acts on opposite ends of the valve plunger but since the area 62 of the left end of the plunger is larger than the area 63 there is a differential which holds the plunger in its right hand position defined by the detent 64. Thus, when the operator throws the starting lever 65 he must overcome this differential pressure in order to throw the valve plunger in a running position. When this has been accomplished, the port 49 is connected by the annular groove 66 to port 67 whereby fluid flows through branch channels 68 and 69 which are connected through a common channel 70 to port 67.

The channel 68 terminates in a port 71 located in the right hand end of the cylinder 24 causing movement of piston 23 to the left whereby the wheel slide will advance at a relatively rapid rate. At the same time the port 72 located in the left end of cylinder 24 is connected to reservoir through channel 73, interconnected ports 74 and 75 of the cycle control valve 48 and channel 76 which leads to the reservoir 54.

The branch channel 69 terminates in ports 77 and 78 of a main pilot valve 79 and port 80 of an auxiliary pilot valve 81. The main pilot valve 79 has a valve plunger 82 which is held in its right hand position as shown in Figure 5 by a spring 83. In this position an annular groove 84 formed in the plunger 82 interconnects port 77 with port 85 whereby the pressure fluid continues through channel 86 to port 87 located in the right hand end of the auxiliary pilot valve 81. This causes a shifting of the auxiliary pilot valve plunger 88 to the left against the compression of a spring 89 whereby the pressure port 80 is interconnected by the annular groove 90 to port 75

91 causing fluid to flow through channel 92 to port 93 located in the right hand end of the feed control valve housing 57. By this time the piston 23 has completed the rapid traverse movement of the wheel slide and the worm 28 has been shifted axially by rotation of the worm wheel 27 until the end of the bearing portion 31 abuts the end of a follower 94 of a cam 95. This positively stops the rapid movement of the wheel slide.

The cam 95, as shown in Figure 3, is keyed to the upper end of a rotatable shaft 96 which is supported for rotation in a housing 97. The cam 95 has a receding peripheral surface 98 whereby upon rotation in a counterclockwise direction it will permit further advance of the worm 28 toward the right under the pressure of the fluid in the right hand end of cylinder 24 acting on the piston 23. The cam also has gear teeth 99 cut in a portion of its periphery and intermeshing with rack teeth 100 formed longitudinally of a feed control piston 101.

This piston is slidably mounted in a cylinder 102 which has ports 103 and 104 located at opposite ends thereof. The port 103 is connected by a channel 105 to port 106 of the feed control valve 57. An adjustable throttle valve 107 is serially arranged in this channel for varying the feed rate. A check valve 108 is connected in parallel across the throttle valve, and so positioned as to stop flow to the feed piston while permitting return flow therefrom.

When the plunger 58 of the feed control valve 57 is shifted to the left by fluid pressure entering port 93 the port 106 is connected by the annular groove 109 to pressure port 56. This will cause fluid to enter the feed cylinder 102 at a rate determined by the setting of the throttle valve 107 and cause rotation of the cam 95 to produce a slow rate of advancing movement of the grinding wheel slide. The receding surface 98 is of such contour that by the time the piston 101 has reached the end of its cylinder it will have moved out of engagement with the follower 94 due to the fact that in the meantime the worm 28 has hit the positive stop 40. It will thus be apparent that although the cam acts to control the feed rate it does not act as a positive stop for determining the final infeed position of the grinding wheel slide.

It will be obvious that during rotation of the cam 95, its supporting shaft 96 to which it is keyed will also be rotated, and this shaft is provided with a pinion portion 110 which is engaged by a rack plunger 111 whereby upon counterclockwise rotation of the pinion 110 as viewed in Figure 4 the plunger 111 will move upward and engage the end of the main pilot valve plunger 82.

This will shift the plunger against the compression of spring 83 until the annular groove 112 in the plunger interconnects the pressure port 78 with a port 113. At the same time port 85 will be connected, by the annular groove 84, with port 114 whereby the fluid in the right hand end of the auxiliary pilot valve 81 is connected to the reservoir channel 76. This will permit the auxiliary pilot valve plunger to be returned to its starting position by spring 89, thereby connecting channel 92 leading from the right hand end of the feed control valve 57 to a reservoir port 115. The result of this is that the fluid which shifted the feed control valve plunger is now exhausted to reservoir, and pump pressure is connected through port 113 and an adjustable throttle or delay valve 116

to port 117 of valve housing 57 tending to shift the plunger 58 to the right. It will thus be obvious that while the plunger 58 is slowly moving to the right, that the grinding wheel slide has advanced the full length of its movement and is gradually sparking out.

The length of time that the grinding wheel will be finishing the surface will depend upon the setting of the delay valve 116. When the valve plunger 58 has completed substantially one-half of its movement, or in other words as soon as the valve spool 118 cracks the port 56 fluid pressure will flow to port 59' and branch 119 to the auxiliary cylinder 120 located in the left hand end of the valve housing 57 so that pressure will act on the end 121 of the plunger 58 more effectively and the further the plunger 58 moves to the right the faster will the fluid pressure run into the chamber 120 whereby the plunger 58 becomes self-actuating to complete the last half of its shifting movement.

When the plunger 58 has returned, the pressure fluid now being admitted to channel 60 through port 59' will enter port 61 of the starting valve and shift plunger 47 to the right. The fluid entering the left end of the housing 48 will continue through port 122 after it has been uncovered and channel 123 to port 104 of the feed cylinder 102. Shifting of the plunger 47 will also reverse the connections to cylinder 24, port 71 now being connected to reservoir through port 124 and port 72 being connected to pressure through the interconnection of ports 49 and 14. Thus, the piston 23 and the feed piston 101 will rapidly return to their starting positions.

Since the amount of excess stock on work coming to a grinding machine has a wide variation, provision is made for varying the length of the feed stroke so that the machine may be operated efficiently at all times. As previously described, the feed control cam has a receding surface which means that the radius of the periphery gradually reduces from the radial line 125, which is coincident with the axis of the follower when the feed piston 101 is in its maximum return position, to the radial line 126 which is coincident with the axis of the follower when the feed piston is in its maximum advanced position.

Therefore, if the feed piston is not permitted to return to its maximum return position but some distance short of that position, the length of the particular cam radius which is coincident with the axis of the follower will be less than the radius 125, which means that the rapid traverse movement of the wheel slide will be greater, and therefore the grinding wheel will approach the work a greater distance before its rate of movement is changed to a feeding rate. Means are, therefore, provided for varying the return position of the feed piston 101 and thereby of the cam 98 whereby the length of the rapid traverse movement may be increased and the length of the feed movement correspondingly decreased in accordance with the stock removal requirements of a given work piece.

The total fall in the arcuate periphery of the cam between the radii 125 and 126 represents, of course, the maximum length of feeding movement, and has been determined to take care of the maximum requirements of the machine, and the means referred to above have been provided for reducing the fall in accordance with particular requirements. The mechanism for in-

versely varying the length of the rapid traverse stroke and the feed stroke, it being remembered that the sum of these two distances must always be equal to the total movement permitted by the positive stops 39 and 40 for the worm 28, is more particularly shown in Figure 4.

This mechanism comprising a rack plunger 127 which is slidably guided in a bore 128 of the housing 97 and in intermeshing relation with the pinion 110 integral with the cam supporting shaft 96. As the feed piston returns it rotates the pinion 110 in a clockwise direction as viewed in Figure 4, thereby shifting the plunger 127 toward the left. An adjustable stop 129 is threaded in the housing 97 in axial alignment with the plunger 127 whereby the return position of the feed piston is determined by engagement of plunger 127 with the stop 129. A shaft 130 connects this threaded stop through gearing 131 to a manually adjustable dial 132 located on the front of the machine as shown in Figure 1. This dial may be suitably graduated to indicate the length of feed movement which should approximate the amount of excess stock to be removed from a work piece. Thus, by means of this mechanism the starting position of the cam may be varied and by such variation the relative lengths of the rapid movement and the feed movement are inversely changed.

Attention is invited to the fact that the starting valve 48 is in effect a reversing valve for the rapid traverse piston and a control valve for one end of the feed piston. In other words, it controls the admission of fluid pressure to effect the return stroke of the feed piston, but since the port 122 is closed during the advance of the feed piston a check valve 133 is so connected to channels 123 and 60 as to by-pass exhaust fluid around the closed port. An additional check valve 134 is provided in parallel with the throttle or delay valve 116 to permit exhaust of fluid to reservoir through port 117 of the feed control valve when the plunger 58 is shifted to the left to start the feeding movement.

There has thus been provided an improved feed control mechanism for a grinding machine which is simple and rugged in construction, easy to adjust, and efficient in operation.

What is claimed is:

50. In a grinding machine having a work support and a grinding wheel support, the combination of an infeeding mechanism therefor including an intermeshing worm and worm gear, motion transmitting means connecting the worm gear to the movable support, a manually operable means for rotating said worm to adjust the support through the worm gear, a fluid operable piston for shifting the movable support at a rapid rate whereby said worm is shifted axially by reaction of the worm gear thereon, a cam for limiting the extent of axial movement of said worm, and means to actuate said cam to produce additional movement of the support by the piston at a feeding rate under control of said cam.
55. In a grinding machine having a work support and a grinding wheel support, the combination of means for effecting relative movement between the supports including a power operable member, motion transmitting means connecting the member for movement of one of said supports at a rapid rate, a feed control cam, a part shiftable jointly with the support into abutting engagement with said cam for stopping said rapid movement, means to actuate said cam to permit further movement of said part and thereby of
- 60.
- 65.
- 70.
- 75.

said support at a feed rate, a positive stop, said cam having a receding profile of such extent that the cam will eventually move out of engagement with said part whereby said positive stop will determine the final infeed position of said support.

3. In a grinding machine having a work support and a grinding wheel support, the combination of means for effecting a relative infeeding movement of the grinding wheel support including a first power operable member for effecting a rapid advance movement of said support, means for positively stopping said advance movement including a cam, and a part movable with said support and engageable with said cam, a second power operable member for actuating said cam, said cam having a receding surface to permit further advance of said support at a feed rate, and a final positive stop effective independently of said cam for determining the final infeed position of said support.

4. In a grinding machine having a work support and a grinding wheel support, the combination of an infeeding mechanism including power operable means for effecting a rapid advance of the grinding wheel support, means subsequently operable for producing a feeding movement including an infeed control cam, a cam follower movable with the support into engagement with said cam, a fluid operable piston for actuating the cam to produce a feeding movement, means trip operable by the piston for reversing its direction of movement, and adjustable means for determining the extent of the return movement of the piston and thereby the starting position of said cam.

5. In a grinding machine having a work support and a grinding wheel support, the combination of an infeeding mechanism including power operable means for effecting a rapid advance of the grinding wheel support, means subsequently operable for producing a feeding movement including an infeed control cam, a cam follower, movable with the support for engaging said cam and stopping the rapid movement, a fluid operable piston for actuating the cam to produce the feeding movement, means trip operable by the piston for reversing its direction of movement, and adjustable means for determining the extent of said return movement and thereby the starting position of said cam, said adjustable means including a threaded stop and a plunger movable in synchronism with the piston for engagement with said stop.

6. In a grinding machine having a work support and a grinding wheel support, the combination of means for moving one of said supports toward and from the other including a worm wheel and a rotatable axially movable worm, a housing supporting said worm and having positive stops at each end for determining the extent of axial movement of said worm and thereby the extent of movement of said support for either rotation or axial shifting of the worm, power operable means for effecting part of said axial movement at a rapid rate, and additional means for causing the rest of said movement to take place at a feed rate.

7. In a grinding machine having a work support and a grinding wheel support, the combination of a hydraulic control circuit for effecting a relative infeeding movement between said supports including a rapid traverse piston, a feed piston, a source of pressure, a starting valve for connecting fluid pressure to said rapid traverse

piston, a feed control valve, a pilot valve and an auxiliary pilot valve, means operable by the starting valve for connecting fluid pressure to said pilot valves, means in the main pilot valve to effect hydraulic shifting of the auxiliary pilot valve and thereby effect a connection of shifting pressure to the feed control valve, means operable by the feed control valve for connecting pressure to said feed piston, and means operable by the feed piston for shifting said main pilot valve to cause return movement of both of said pistons.

8. In a grinding machine having a work support and a grinding wheel support and means intervening said supports permitting a relative movement in a direction toward and from each other, of means for effecting said relative movement including a first actuating piston having an extended axial movement, a second member having a limited axial movement, means interconnecting said axially movable elements, whereby the member having limited movement determines the extent of movement of the piston, and means for varying the phase relationship of said parts whereby the potential zone of axial movement of the piston is varied, and additional means interconnecting the piston and one of the supports for effecting movement of the support in accordance with and through the selected zone of activity of the piston.

9. In a grinding machine having a work support and a grinding wheel support and means intervening said supports permitting a relative movement in a direction toward and from each other, of means for effecting said relative movement including a first actuating piston having an extended axial movement, a second member having a limited axial movement, means interconnecting said axially movable elements, whereby the member having limited movement determines the extent of movement of the piston, and means for varying the phase relationship of said parts whereby the potential zone of axial movement of the piston is varied, additional means interconnecting the piston and one of the supports for effecting movement of the support in accordance with and through the selected zone of activity of the piston, a shiftable abutment having a portion projecting to engage the axially movable member, and an additional piston mechanism reacting on the abutment for variably determining the positioning thereof and thus the rate of movement of the shiftable support.

10. In a grinding machine having a work support and a grinding wheel support and means intervening said supports permitting a relative movement in a direction toward and from each other, of means for effecting said relative movement including a first actuating piston having an extended axial movement, a second member having a limited axial movement, means interconnecting said axially movable elements, whereby the member having limited movement determines the extent of movement of the piston, and means for varying the phase relationship of said parts whereby the potential zone of axial movement of the piston is varied, additional means interconnecting the piston and one of the supports for effecting movement of the support in accordance with and through the selected zone of activity of the piston, a shiftable abutment having a portion projecting to engage the axially movable member, an additional piston mechanism reacting on the abutment for variably determining the positioning thereof and thus the rate of movement of the shiftable support, and addi-

tional means for variably determining the limit of movement of the second piston and thus the ultimate position of the abutment controlled thereby.

11. In a machine of the character described, the combination with a pair of relatively adjustable supports, of means for effecting relative rapid traverse feed movements thereof including a drive shaft, a hydraulic motor for effecting rotation of the shaft, a driving connection from the shaft to the movable support, and means for determining the extent and rate of rotation of the shaft including a worm wheel carried by the shaft, a worm housing in fixed relation to one of the supports, a worm rotatably and translatably mounted in the housing, means for rotating the worm to effect through the worm gear rotary adjustment of the shaft and coupled hydraulic motor and thus the position of the movable support, a first means for limiting the axial movement of the worm, a variable positionable abutment projectable into the path of movement of the worm, and means including a variable speed hydraulic motor coupled with the abutment for determination of the positioning thereof, whereby said latter motor by reaction on the worm determines the rate of feeding movement of the shiftable support.

12. In a machine of the character described, the combination with a pair of relatively adjustable supports, of means for effecting relative rapid traverse feed movements thereof including a drive shaft, a hydraulic motor for effecting rotation of the shaft, a driving connection from the shaft to the movable support, and means for determining the extent and rate of rotation of the shaft including a worm wheel carried by the shaft, a worm housing in fixed relation to one of the supports, a worm rotatably and translatably mounted in the housing, means for rotating the worm to effect through the worm gear rotary adjustment of the shaft and coupled hydraulic motor and thus the position of the movable support, a first means for limiting the axial movement of the worm, a variable positionable abutment projectable into the path of movement of the worm, means including a variable speed hydraulic motor coupled with the abutment for determination of the positioning thereof, whereby said latter motor by reaction on the worm determines the rate of feeding movement of the shiftable support, and means for variably limiting the extent of movement of the abutment controlling motor and thus the ultimate positioning of the worm and support.

JACOB DECKER.
